UNITED STATES PATENT OFFICE.

ALEXANDRE GUINDON, OF ROCKLAND, ONTARIO, CANADA.

COMPUTING MACHINE.

1,416,194.

Specification of Letters Patent. Patented May 16, 1922.

Application filed July 15, 1920. Serial No. 396,415.

To all whom it may concern:

Be it known that I, ALEXANDRE GUINDON, a subject of Great Britain, and resident of Rockland, in the Province of Ontario, Dominion of Canada, have invented certain new and useful Improvements in Computing Machines, of which the following is a specification.

This invention relates to improvements in computing machines, and the objects of the invention are to construct a machine which is simple and effective and in which arithmetical calculations such as multiplication can be rapidly performed, to render the several parts easily accessible for inspection, and generally to adapt the machine to better perform the functions required of it.

With the above and other objects in view, the invention consists essentially of the improved construction and arrangement of parts particularly described and set forth in the following specification and accompanying drawings forming part of the same.

In the drawings:

Figure 1 is a perspective view of the improved computing machine.

Fig. 2 is a transverse section of the same.

Figure 3 is an enlarged plan view of the roller which shows the methods of computing tens and hundreds and the pointer mechanism cooperating with the said roller.

Figure 4 is a fragmentary side elevation showing the lever means for actuating the pointer illustrated in Figure 3.

Figure 5 is a side elevation of the gearing controlling the rotation of the drum.

Figure 6 is a plan view of the same.

Figure 7 is a perspective view of the drum.

Figure 8 is a perspective view of the adjustable stop mechanism which coacts with the drum actuating lever.

Like characters of reference refer to like parts in the several figures.

Referring to the drawings: A represents the improved computing machine comprising a casing 10, in which the drum 12 is rotatably mounted, the drum spindle 13 being provided with a gear 14 thereon. The gear 14 meshes with a gear 15 mounted on an intermediate spindle 16 which also carries a pair of ratchet wheels 17 and 18, the teeth of which are disposed in opposite directions.

A lever 19 is mounted on the spindle 16 and carries a pair of detents 20 and 21 designed to coact with the ratchet wheels 17 and 18 respectively, and the detents 20 and

21 are actuated by the rods 22 and 23 which are connected to the hand grips 24 and 25 pivotally attached to the upper end of the hand lever 19. A lever 26 is pivotally mounted in the casing and has an offset end 27 designed to be moved into engagement with the gear 15 as will hereinafter be explained.

The spindle 16 carries a gear 28 which meshes with the gear 29 and the gear 29 is mounted on a spindle 30 which is movable so that the said gears may be unmeshed if such is found necessary.

The spindle 30 is provided with a threaded end 31 carrying a pointer 32 which overhangs a roller 33 mounted on a frame 34 adjacent to the casing 10. The spindle 16 is engaged by a U-shaped member 35 which is pivotally attached to the lever 36 and this lever is in turn pivoted to the frame 34.

As the lever 36 is rocked, the gear 29 will be moved into or out of mesh with the gear 28.

A pair of levers 37 are provided pivotally mounted in the casing 10 and carrying a stop member 38, and these levers are formed of resilient material and coact with the spaced arcuate racks 39 also mounted in the casing 10.

In the casing 10 a rectangular orifice 40 is provided in which the levers 37 and 19 operate and a second rectangular orifice 41 is provided in which the lever 26 operates.

The drum 12 is graduated being divided by arcuate lines and longitudinal lines into squares each of which are numbered and an index 42 is provided slidably mounted above the slot 43 in the casing 10, and behind this index 42 a plate 44 is provided which is also numbered.

One side of the orifice 40 is also numbered as shown at 45.

When the machine is in use, and a determination has to be made, then the operator moves the index 42 to that denomination which the price of an article is given and he then actuates the levers 37 to bring them to the number by which this price is to be multiplied.

He then actuates the lever 19 and rotates a drum 12 and the result of the multiplication may be read off on that portion of the drum visible just above the index 42.

If a second multiplication is to be made of the result obtained by another number, then the operator actuates the lever 26 to

engage the offset end 27 with the gear 15 so that he holds the drum against rotation and then resets the lever 19 to its zero position.

The levers 37 are now adjusted until they coincide with the number by which the last results is to be multiplied. The operator now releases the lever 26 and actuates the lever 19 to rotate the drum 12 through a further step and the result of this multiplication is then read off at the index 42.

If the result of the multiplication will be such that the numbers could not be obtained on the large drums 12, then the operator actuates the lever 36 to throw the gear 29 into mesh with the gear 28 and on the rotation of the spindle 16 by the lever 19 then the spindle 30 will be rotated and the pointer 32 moved along the graduated drum 33 allowing tens or hundreds to be read off on the said drum while smaller denominations such as units could be read off on the larger drum 12.

From the above description it will be seen that I have invented a computing machine in which ordinary arithmetical calculations may be made with rapidity and accuracy.

As many changes could be made in the above construction and many widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:—

1. A computing machine comprising a casing, a drum rotatably mounted in the casing and having symbols on its periphery, a spindle, gears connecting the spindle with the drum, a pair of ratchet wheels on the spindle having oppositely disposed teeth, a hand lever, detents carried by the lever to coact with the teeth, means for simultaneously actuating the detents, a lever pivoted within the casing and having an offset end designed to engage one of the gears, a gear on the said spindle, a second spindle movable in a direction transversely to its length and having a gear to coact with the last said gear, a pointer threaded on the last said spindle and a roller having graduations thereon underlying the pointer.

2. A computing machine comprising a casing, provided with a longitudinal slot, a drum rotatably mounted in the casing, and having symbols on its periphery, a spindle, gears connecting the spindle with the drum, a pair of ratchet wheels on the spindle having oppositely disposed teeth, a hand lever, detents carried by the lever to coact with the teeth, means for simultaneously actuating the detents, a lever pivoted within the casing, and having an offset end designed to engage one of the gears, a gear on the said spindle, a second spindle movable in a direction transversely to its length, and having a gear to coact with the last said gear, a pointer threaded on the last said spindle, and a roller having graduations thereon underlying the pointer, an arcuate rack on the casing, a lever coacting with the rack and provided with a stop member designed to be engaged by the hand lever, substantially as and for the purpose described.

3. A computing machine comprising a casing, provided with a longitudinal slot, a drum rotatably mounted in the casing and having symbols on its periphery, a spindle, gears connecting the spindle with the drum, a pair of ratchet wheels on the spindle having oppositely disposed teeth, a hand lever, detents carried by the lever to coact with the teeth, means for simultaneously actuating the detents, a lever pivoted within the casing, and having an offset end designed to engage one of the gears, a gear on the said spindle, a second spindle movable in a direction transversely to its length, and having a gear to coact with the last said gear, a pointer threaded on the last said spindle, a roller having graduations thereon underlying the pointer, guide members along the edges of the longitudinal slot and an index slidably engaging with the guide members, an arcuate rack on the casing, a lever coacting with the rack and provided with stop member designed to be engaged by the hand lever, substantially as and for the purpose described.

In witness whereof I have hereunto set my hand in the presence of two witnesses.

ALEXANDRE GUINDON.
